US00D655296S

(12) **United States Design Patent**
Andre et al.

(10) **Patent No.:** US D655,296 S
(45) **Date of Patent:** ** Mar. 6, 2012

(54) **ELECTRONIC DEVICE**

(75) Inventors: **Bartley K. Andre**, Menlo Park, CA (US); **John M. Brock**, San Francisco, CA (US); **Matthew Phillip Casebolt**, Fremont, CA (US); **Brett William Degner**, Menlo Park, CA (US); **Ron Alan Hopkinson**, Campbell, CA (US); **Eugene Kim**, San Francisco, CA (US); **Chris Ligtenberg**, San Carlos, CA (US); **John Raff**, Menlo Park, CA (US); **David Yeh**, Redwood City, CA (US)

(73) Assignee: **Apple Inc.**, Cupertino, CA (US)

(**) Term: **14 Years**

(21) Appl. No.: **29/388,897**

(22) Filed: **Apr. 4, 2011**

Related U.S. Application Data

(62) Division of application No. 29/377,130, filed on Oct. 18, 2010, now Pat. No. Des. 637,192.

(51) **LOC (9) Cl.** **14-02**

(52) **U.S. Cl.** **D14/436**

(58) **Field of Classification Search** D14/411, D14/433, 435.1, 436, 480.1–480.7, 484.1, D14/137, 155, 203.1–203.8, 240; 710/300, 710/301; 439/131, 135–147

See application file for complete search history.

CLAIM

The ornamental design for an electronic device, as shown and described.

DESCRIPTION

FIG. 1 is a top, front, left perspective view of an electronic device showing our new design;
FIG. 2 is a top view thereof;
FIG. 3 is a bottom view thereof;
FIG. 4 is right side view thereof;
FIG. 5 is a left side view thereof;
FIG. 6 is a front view thereof; and,
FIG. 7 is a rear view thereof.

1 Claim, 5 Drawing Sheets
